UNITED STATES PATENT OFFICE.

MAURICE LACHMAN, OF NEW YORK, N. Y., ASSIGNOR TO LACHMAN MANUFACTURING COMPANY, OF NEW YORK, N. Y., A CORPORATION OF DELAWARE.

KEG.

1,112,298.

Specification of Letters Patent.

Patented Sept. 29, 1914.

Application filed June 28, 1912. Serial No. 706,324.

To all whom it may concern:

Be it known that I, MAURICE LACHMAN, a citizen of the United States, and a resident of New York, in the county of New York 5 and State of New York, have invented certain new and useful Improvements in Kegs, of which the following is a specification.

This invention relates to the construction of kegs, barrels or other containers and more 10 particularly to such containers as are made of paper or similar fibrous material.

The main object of the invention is to provide a simple and effective fastener for securing the heads or closures to the body 15 portion of the container.

The invention relates to that class of containers in which the main or body portion is formed of non-metallic material such as paper or a similar substance compressed into 20 a solid mass to take the place of and be a substitute for wood. The heads which may be of any suitable construction are secured to the body portion of the container by fasteners or means which preferably do not 25 enter the material of the body thus preventing fraying or mutilation and adding to the strength.

The invention consists in the novel container as to its details of construction, and 30 combination of parts hereinafter more particularly described and then specified in the claims.

In the accompanying drawings, Figure 1 is a vertical cross-section through a container constructed in accordance with this 35 invention in one of its forms. Fig. 2 is a similar section through the upper part of a container of a modified form. Fig. 3 is a similar section through the upper portion of 40 a container embodying a further modification of this invention. Fig. 4 is a view of a similar section through the upper portion of a container embodying a further modification.

45 The invention is herein shown and will be described as applied to a keg or barrel but it will be understood that it may equally well be employed with other forms or contours of containers as for instance rectangular or square boxes or the like and it is not limited to the particular forms shown.

When the invention is applied to kegs or barrels, the body of the keg or barrel consists preferably of a cylinder of paper or 50 other similar non-metallic material formed

in any desired manner. The cylinder 1 is preferably formed of a number of layers of paper superimposed on each other, preferably by spinning, and compressed into a solid mass, the various layers being preferably united by suitable cement, glue or other adhesive whereby a very rigid wall is attained. The specific manner of forming the body or cylinder forms no part of my invention and further description will be dispensed with. 60 65

2 indicates bands or hoops which are preferably formed of paper as is the made body of the cylinder 1. The hoops or bands 2 may either be formed on the body 1 at the time of forming the body or may be made 70 separately and subsequently cemented or otherwise secured to the periphery of the body.

The head of which there is one at each end 75 of the cylinder is formed in any suitable manner. As shown in Figs. 1 and 3, it comprises a paper disk 3 forming the main closure for the end of the cylinder. The paper disk 3 is secured, in any desired manner, to a metal rim 4. The rim is provided with inner and outer annular flanges: preferably in different planes, the inner flange holding the disk 3 while the outer flange 80 seats on the edge of the container body 1 to 85 protect the raw edge from mutilation.

Referring to the form shown in Fig. 1, the head is secured to the body by fasteners 5 which, as desired, might be wires, strips or continuous bands. In this figure, the fasteners are shown as a plurality of separate strips 5, bent around to encircle the hoops 2, the one end clenching over the outer flange of the head rim 4 while the other end is bent under to engage the under side of the hoop. 90 95 By this construction, the hoop 2 being an integral part of the body 1, the head is securely attached to the body in an obvious manner.

In the form shown in Fig. 2 the fastener 100 for the head is shown as a continuous metal hoop or band 6 which also, at its inner periphery 6', forms a seat for the paper disk 3 which is secured thereto in any desired manner. In this case the band 6 encircles the hoop and its other edge is spun or otherwise forced into engagement with the under side of the hoop 2. 105

Referring to Fig. 3, the fastening band 7 is provided with an annular skirt 8 which 110

is in engagement with the periphery of the body 1 beyond the hoop 2. In this case the outer flange of the head rim 4 is somewhat extended beyond the hoop 2 and beaded into a roll with one edge of the band 7 whereby the band 7 and head rim 4 are locked together. This construction further forms a rolling rim on which the container can be readily transported. 9 indicates a wire or 10 other form of tying device wrapped around the skirt 8 and by means of which the band 7 is securely held to the body 1, in this case the clamping action not being dependent upon the engagement of the band 7 with the 15 under side of the hoop 2.

It will be understood that this invention is capable of various modifications without departing from the spirit thereof as set forth in the appended claims.

20 In the form shown in Fig. 4 the paper disk 3 is held to an annular rim 10 as in the forms shown in Figs. 1 and 3, that is the rim 10 is provided with a lower flange which forms a seat for the disk 3, the metal of the 25 rim being then spun around the edge of the disk and doubled back on itself into engagement with the upper surface of the disk 3. By this construction the disk is firmly held between the flanges of the rim 10 without 30 the necessity of employing any other fastening devices. As in the form shown in Fig. 2, the rim 10 is forced over the hoop on the outer periphery of the body 1 and under the lower edge thereof. If desired, 35 staples or rivets 11 may be employed to fasten the rim to the body in which case it is not absolutely necessary to force the edge of the rim 10 under the hoops 2.

What I claim as my invention is:—

40 1. A container comprising a body of paper-like material, a paper hoop cemented to the periphery of the body, a head, a continuous metal band engaging said head and extending over the rim of this container to

the outside of said paper hoop, said band 45 being provided with a skirt adapted to engage the periphery of the body beyond the hoop and means for tying said skirt to said body.

2. A container comprising a body of 50 paper-like material, a paper hoop cemented to the periphery of the body, a head, a continuous metal band engaging said head and extending over the rim of this container to the outside of said paper hoop, said band 55 being provided with a skirt adapted to engage the periphery of the body beyond the hoop and a wire wrapped around said skirt to bind said band to said body.

3. A container comprising a body of 60 paper-like material, a paper hoop secured to the periphery of said body, a head provided with a flange resting on the edge of said body and a metal band fastener on the exterior of said hoop and adapted to engage 65 the under side of the same whereby the band is prevented from removal in one direction, the edge of said band being spun with the outer edge of the head flange to lock the two together.

70 4. A container comprising a body of paper-like material, a paper hoop secured to the periphery of said body near the end thereof, a head, a continuous metal band engaging said head and extending over a 75 portion of said paper hoop and an annular metallic member covering said hoop, and means for maintaining said parts in the relation specified to retain said head within said body.

80 Signed at New York in the county of New York and State of New York this 6th day of June A. D. 1912.

MAURICE LACHMAN.
